KEY CONTAINER

Allan D. Mitchell, Detroit, Mich.

Application April 15, 1947, Serial No. 741,629

4 Claims. (Cl. 70—456)

1

This invention relates to key containers and particularly to a container arranged to hold a plurality of keys in retracted positions from which they can be selectively projected for use.

It is known to provide key containers in which one or more keys may be secured for movement between a position retracted within the container and a projected or extended position in which the key bit projects beyond the container for insertion into the corresponding lock. Such devices as previously proposed however have been unduly expensive, bulky, difficult to insert the keys into and remove keys from; unreliable in projecting the keys to a usable position, and of insufficient strength to withstand the torque incident to rotating the key in the lock.

It is among the objects of the present invention to provide an improved key container which is inexpensive to manufacture, of minimum size and weight, of adequate strength to withstand a long period of service without damage or breakage, which is arranged for the easy insertion and removable of keys so that the keys can be changed whenever desired and a key may be quickly and conveniently removed from the container if it is desired to use it separately, which utilizes a minimum number of different parts, and is neat and attractive in appearance.

Other objects and advantages will become apparent from a consideration of the following description in conjunction with the accompanying drawing, wherein:

Figure 1 is a top plan view of a key container illustrative of the invention.

Figure 2 is a longitudinal sectional view on the line 2—2 of Figure 1.

Figure 3 is a perspective view of a slide block for receiving the handle or butt portion of a key.

Figure 4 is a cover for the block shown in Figure 3.

Figure 5 is a perspective view of a fragmentary portion of the right hand end of the key container as viewed in Figures 1 and 2.

Figure 6 is a perspective view of an end cover member for the key container, and

Figure 7 is a longitudinal sectional view similar to Figure 2 showing a somewhat modified form of key container illustrative of the invention.

Fig. 8 is a section taken along line 8—8 of Fig. 2.

With continued reference to the drawing, the improved key container comprises a body portion, generally indicated at 10, of elongated rectangular shape, and an end cover member generally indicated at 11.

The body member 10 has a top wall 12 provided with a plurality of spaced longitudinal slots 13

2

each having at one end thereof an extension or off-set 14 and intermediate the length thereof a second off-set or extension 15, a solid bottom wall 16, two side walls 17 and 18 and an end wall 19 provided with spaced apertures 20 respectively in alignment with the slots 13 and through which the bit or blade portions of the keys are extendible when moved from the retracted position, illustrated in Figure 2, to their extended or projected position.

Spaced partitions 21 extend between the bottom wall 16 and top wall 12 of the body member 10 substantially parallel to the side walls 17 and 18, dividing the body member into a plurality of separate rectangular compartments each of which communicates with a respective slot 13 in the top wall 12.

A slide block, as generally indicated at 22, is slidably mounted in each compartment provided by the side walls 17 and 18 and the partitions 21 to receive the handle or butt portion of a respective key and maintain the key in operative position in the corresponding compartment.

The slide block 22, as particularly illustrated in Figure 3, comprises a rectangular side member 23 provided along each edge thereof with a marginal flange, as indicated at 24, the outer edge of these flange portions being bent over to a position substantially parallel to the side member 23, as indicated at 25. The flange along one edge of the member 23 has an aperture 26 therein of a size to closely fit the neck portion of a key between the blade portion and the butt or handle thereof to maintain the key in the operative position illustrated in Figure 2.

A portion of the flange 24 at right angles to the portion in which the aperture 26 is provided is bent upwardly to provide a button 27 by means of which the key holder 22 may be moved lengthwise of the corresponding compartment in the body member 10. The upstanding tongue 28 of the button extends through the corresponding slot 13 in the top wall of the body member and the head of the button overlies the edges of the slot and has a bearing on the upper surface of the top wall 12 to facilitate movement of the key holder in the compartment. The entire key holding block 22, or the portion 28 thereof, is formed of resilient material so that the portion 28 may be positioned in the recess 15 of the corresponding slot when the key is in retracted position and may be moved out of the recess into the slot when the corresponding key is moved to its extended or projected position and may be received in the corresponding recess 14 when the key has been projected. By this means the key is locked in

either its retracted or projected position so that the keys cannot accidentally be lost from the container, and will not be pushed back into the container while being inserted in a lock.

The cover plate 29 fits over the open side of the key holder 22 within the flange portion thereof and has a perpendicular extension 30 which fits behind the key to position the key toward the portion of the key holding block in which the aperture 26 is provided. In the case of a key having a small butt or handle portion additional packing members or shims may be interposed between the member 30 and the adjacent end of the key handle to retain the key firmly in the holder.

The slots 13 extend entirely to the right hand end of the body 10, as viewed in Figure 1, and particularly shown in Figure 5, so that the key holders may be inserted in the compartments provided by the partitions 21 and the tongue portions 28 may enter into the corresponding slots. When it is desired to remove a key from the container or add a key to the container the end closure member 11 is removed from the body 10, the desired key holder 22 is removed from the corresponding compartment, the key either removed therefrom or inserted therein, and the key and key holder returned to operative positions in the corresponding compartment in the body of the key container. The partitions 21 extending transversely of the body 10 render this member extremely strong and durable and the connections between the key and the body through the intermediacy of the key holder 22 is of adequate strength to support torque forces exerted on a key in unlocking a lock.

The end closure member 11 is an integral, preferably molded, rectangular body having an end wall 32, a top wall 33, side walls 35 and 36 and transverse ribs 37 extending between the top wall 33 and bottom wall 34 substantially parallel to the side walls and dimensioned to fit into the ends of the longitudinal compartments provided in the body member 10. The upper ends of the ribs have cut-away portions 38 to receive the ends of the portions of the top wall 12 of the body portion which extend laterally from the top ends of the partitions 21, and the side wall 17, so that the end member fills all of the spaces at the end of the body member and fits tightly over the end portions of the body member walls to reinforce the end of the body member through which the slots 13 extend.

This end member may be secured in position on the end of the body 10 by suitable detents 39 provided interiorly of the side walls of the end closure member and engaging in recesses provided in the outer surfaces of the side walls of the body member, the two members being sufficiently resilient to permit disengagement of these latching devices by manual pressure on the side walls of the body portion 10.

The body member 10 and the end closure member 11 are preferably formed of a moldable plastic material, such as synthetic resin, and have adequate strength and resiliency to function in the manner indicated above.

In the modified arrangement shown in Figure 7, the structure is the same as that described above except that the key 40 is provided with a modified butt or handle portion 41 of rectangular shape materially smaller than the handle portion 42 of the key 43 shown in Figure 2. This permits the use of a much smaller key holding member 22, and in consequence, reduction in height of the

entire key container. For this modified arrangement the key may be provided with rectangular shaped handle portion of the proper size to fit the key holders provided therefor in which case the key itself enters into the novel combination of the invention.

A pair of body members 10 may be connected in endwise relation by a cover (not shown) and which is ordinarily constructed to the cover 11 except this cover will be grooved inwardly from opposite sides thereof.

The invention may be embodied in other specific forms without departing from the spirit or essential characteristics thereof. The present embodiment are therefore, to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed is:

1. A key container comprising a body member having a top wall with spaced longitudinal slots extending to one end thereof, side walls and a bottom wall, an end wall at the other end of said top wall and having vertical slots therein, said slots being longitudinally aligned with the slots 30 in the top wall, and longitudinal partitions extending from said top wall to said bottom wall parallel to said side walls to provide separate key receiving compartments in said body member, said compartments being aligned with the slots in the top and end walls, a rectangular key holder slidable in each compartment and having a button extending through the corresponding slot in said top wall to selectively move the key holders relative to the slotted end wall and project the shanks of keys housed at their butt ends in the holders, and an end closure member for the open end of said body member, each of said slots having two spaced recesses laterally associated therewith to engage the corresponding buttons and lock said key holders in key extending or key retracting positions.

2. A key container comprising a rectangular housing having elongated opposing pairs of side walls and transverse end walls, one of said end walls being detachable and the opposing end wall being formed with transversely spaced vertical slots, one of said side walls being formed with longitudinally disposed slots longitudinally aligned with the slots in the end wall, longitudinal partitions formed vertically in said housing and dividing the housing into a plurality of compartments, said compartments being aligned longitudinally and vertically with the slots in the side and end walls, key holders slidably mounted in each compartment for housing the butt ends of keys which have their shanks projecting therefrom, and an actuator connected to each holder, said actuators extending through the slots in the side wall whereby the holders can be selectively moved relative to the slotted end wall to extend the shanks of the keys through the slots in the end wall.

3. A key container comprising a rectangular housing having elongated opposing pairs of side walls and transverse end walls, one of said end walls being detachable and the opposing end wall being formed with transversely spaced vertical slots, one of said side walls being formed with longitudinally disposed slots longitudinally aligned with the slots in the end wall, longitudinal par-

titions formed vertically in said housing and dividing the housing into a plurality of compartments, said compartments being aligned longitudinally and vertically with the slots in the side and end walls, key holders slidably mounted in each compartment for housing the butt ends of keys which have their shanks projecting therefrom, and an actuator connected to each holder, said actuators extending through the slots in the side wall whereby the holders can be selectively moved relative to the slotted end wall to extend the shanks of the keys through the slots in the end wall, and said slotted side wall having recesses at opposite ends of the slots therein, wherein said actuators can extend to latch the holders in projected or retracted position.

4. A key container comprising a body member of substantially rectangular shape having a vertically slotted end wall and an open end, longitudinal partitions dividing the interior thereof into separate key receiving compartments of rectangular shape, one of said side walls of the body member having longitudinal slots formed therein, a rectangular key holder slidably received in each compartment, each key holder comprising a rectangular side member having flanges along the four edges thereof, said compartments being

aligned with the slots in the side and end walls, one of the flanges of the side member being formed with an aperture for receiving the neck portion of a key between the shank and butt portions of the key, a rectangular cover member fitting inside of said flanges, and a button extending from a flange perpendicular to said one flange portion, and disposed through a slot in the side wall for moving the holder relative to the slotted end wall and extend the shank of the key, and an end closure member for the open end of said body member.
